CHARLES L. PEIRCE, JR., OF PITTSBURGH, PENNSYLVANIA.

SHEET-METAL POLE-ARM.

1,175,077.

Specification of Letters Patent. Patented Mar. 14, 1916.

Application filed May 4, 1914. Serial No. 836,113.

To all whom it may concern:

Be it known that I, CHARLES L. PEIRCE, Jr., a citizen of the United States, and a resident of Pittsburgh, in the county of 5 Allegheny and State of Pennsylvania, have invented certain new and useful Improvements in Sheet-Metal Pole-Arms, of which the following is a specification.

My invention relates to sheet metal pole 10 arms and contemplates improved construction better adapted to the need of the present day in the electrical field.

The tendency at the present time is to get 15 away from wooden pole arms chiefly because such arms are unable to withstand the severe strains to which they would be subjected under service in heavy power work. Furthermore, wood is an uncertain commodity and such uncertainty should not exist 20 particularly in high tension service work. Pole arms have been constructed of commercial forms of iron and steel, as for example angle bar, channel bar, or pipe, but in order to get the necessary strength these arms were 25 made of heavy stock, there being an over sufficiency of iron or steel but not the proper distribution thereof to get the strength where desired. The tendency is also to use steel pins in connection with metal arms in order 30 to have all metal insulator supports.

The general object of my invention is to produce metallic pole arms which require less metal but which have better distribution thereof and greater strength than metal 35 arms heretofore used.

More in detail, the main object of the invention is to build up a pole arm of sheet metal and of such form that it will be very light yet exceedingly strong, and the cost 40 of manufacture will be greatly reduced.

In connection with the old type of pole arms built up of commercial forms such as angle iron, channel iron, pipe, or the like, where the metal is of considerable thickness, 45 straps could readily be used to secure pins to the arms. However, where the arm is built up of sheet metal which is comparatively thin, straps might have a tendency to crush the metal, and another object is therefore to provide such form of sheet metal arm as will enable pins to be rigidly secured thereto by short ordinary bolts or hook bolts.

Generally speaking, the pole arm of my invention comprises a channel shaped body 55 bent up of sheet metal which is secured to a flat base or cross arm engaging wall, this

base projecting beyond the edges of the body to form flanges about whose edge hook bolts may engage or which may be provided with bolt holes for receiving bolts to secure pins 60 to the arm, and other holes may be provided in the flanges in order that braces may be secured to the arm.

Sheet metal pole arms have been constructed heretofore, see my co-pending application Serial No. 737,366, filed December 18, 1912. However, in the construction in this co-pending application the pins are applied in the ordinary manner, that is, 65 holes are provided in the top wall through which the shanks of pins project. With this arrangement the pins cannot always be economically secured, and furthermore, downward service strain or pressure on the pins is in a plane offset from the vertical plane 70 of support of the arm on the pole, the arm therefore tending to twist under very heavy loads. However, my improved construction involves the clamping of pins against the pole engaging base of the arm which will 75 bring the downward service pressure on the pins into the vertical plane of the arm support on the pole, and where the arm is set in a gain provided in the pole the downward pressure on the pins will be in the 80 plane of the gain and the bolts supporting the arm will be relieved of considerable 85 strain.

The various features of the invention will be clearly understood by reference to the accompanying sheet of drawings in which— 90

Figure 1 is a perspective view of part of a pole with my improved cross arm structure applied thereto, Fig. 2 is a rear view of one end of the arm showing more clearly 95 the manner of securing a pin thereto, Figs. 3, 4 and 5 are end views of the arm showing modified forms of body therefor; Fig. 6 is an end view showing another modified arrangement, and Fig. 7 is an end view showing still another modified arrangement. 100

The arm comprises essentially a body part 10 bent into generally convex form from a strip of sheet metal, and a base 11 in the form of a band of sheet metal, this base being preferably flat. In the forms shown in Figs. 1 to 5 the channel shaped body part 10 has the flat end sections or flanges 10^a and 10^b, and the longitudinal edge sections 11^a and 11^b of the base are curled over to intimately surround the flanges 10^a and 10^b. After thus securing the body and base to- 105 110

gether they may be rigidly secured together by means of rivets engaging through the flanges and curled over sections, but preferably spot welding is resorted to to secure the ends rigidly together so that there is absolutely no chance for any relative movement between the body part and base. If the body and base were not rigidly secured together and any relative movement were possible the arm could twist and would do so under heavy strain. However, by securing the edges of the parts together the structure is just as rigid as though it were formed integrally. At suitable intervals the flange sections of the structure may be punched to provide bolt holes 12 for the purpose of securing pins thereto or for the purpose of bolting the upper ends of braces 13 to the arm. The arm is secured to a pole such as *p* by means of through bolts or lag screws 14 and 15 passing through the center bolt holes provided in the upper and lower flanges of the structure. Where the pole is flat the arm is usually secured with its base against the flat face of the pole. When applied to an ordinary cylindrical wooden pole as shown in Fig. 1, a gain 16 is usually cut into the pole into which the arm is set. In Figs. 1 and 2 I have shown pins 17 secured against the outer face of the base 11 by means of bolts 18 and 19 passing through the upper and lower flanges of the structure. With this arrangement of the pins, the weight and pressure thereon will be substantially in the plane of the connection of the arm with the pole, that is, the pressure on the pins is substantially in the plane of the base 11, and in the plane of the gain 16. Such positioning of the pins will prevent twisting tendency of the arm under very heavy weight. The convex body part 10 by being rigidly secured to the base will act as a brace to prevent bending of the arm, either vertically or horizontally. Yet, in order to withstand these strains the sheet metal used can be very thin, this being on account of the rigid structure described. Furthermore, the arm will be very light and can be readily handled. It can also be manufactured very cheaply and the cost of shipping is greatly reduced on account of its lightness.

The insulator pins shown do not themselves form part of this invention but they are particularly adaptable for use in connection with the arm described. The pins shown are each bent up of a length of channel iron to leave along the lower end thereof the slot 20 of a width sufficient to receive the bolts 18 and 19 for securing them to the arm structure.

In Figs. 3, 4 and 5 body parts of modified shape are shown. In Fig. 3 the body 10^c instead of being semi-circular as in Fig. 1, is of U-shape cross-section. In Fig. 4 the body 10^a is of V-shape cross section and in

Fig. 5 the body 10^e is also of V-shape cross section except that the top wall *x* is horizontal. In each of the forms shown in Figs. 3, 4 and 5, the body part has the upper and lower flat sections or flanges 10^a and 10^b intimately received by the curled over edges 11^a and 11^b of the flat base 11 to form seams of which the layers are intimately secured together, preferably by welding.

In Fig. 6 is shown a semi-circular body 10 with the end flanges 10^a and 10^b, but the base 11 does not have its longitudinal edges curled over as in Figs. 1 to 5, the flanges 10^a and 10^b engaging the base along its straight edges and being welded thereto.

In Fig. 7 another form is shown which is particularly adaptable for receiving the hooked ends of bolts for securing pins to the structure. As shown, the body part 10 has again the longitudinal flanges 10^a and 10^b while the base 11 has the short flanges 11^f and 11^g extending at right angles from the base and beyond the flanges 10^a and 10^b, these flanges being secured to the base preferably by welding. The projecting edges of flanges 11^f and 11^g serve to receive the hooked ends *e* of fastening members extending from the pins. As shown, the pin 21 has a bracket 22 secured thereto whose hooked end *e* receives the edge of the upper flange 11^f of the arm structure while at the lower end a bolt 23 passes through the pin whose hooked end *e* receives the edge of the lower flange 11^g. When the pin is to be applied the bracket 22 is hooked over the top edge 11^f and the bolt 23 then slipped through the hole from the front and the nut 24 applied and the pin locked in place. It is evident, of course, that either brackets or bolts could be used both above and below. It is also evident that the arm structure in Fig. 7 could have in addition to the hook receiving flanges, bolt holes by means of which pins, for example like those in Fig. 2, could be secured to the arm.

The arm parts can be formed and secured together while the sheet metal is in a soft and pliable condition whereafter tempering or other treatment can be resorted to to harden and strengthen the metal as desired. Also after the arm has been formed it is preferably heavily galvanized to protect it against the weather.

I do not of course desire to be limited to the exact constructions, forms, or treatments shown and described as modifications may be possible which would still come within the scope of the invention.

I claim the following:

1. A pole arm structure comprising a base in the form of a flat piece of thin sheet metal, a sheet metal strengthening member of arch shaped cross section extending full length of said base and having its edge sections deflected into a common plane to en-

gage the base adjacent the edges thereof, said deflected edges of the strengthening member being rigidly secured to the base throughout the extent thereof to form 5 flanges for receiving insulator supports, and insulator supports secured to said flanges.

2. A pole arm structure comprising a base in the form of a strip of sheet metal, a sheet metal strengthening member of arch 10 shaped cross section extending full length of said base and having its edge sections deflected outwardly to a common plane to engage with said base, the longitudinal edge sections of said base being bent over to

overlap said strengthening member edge 15 sections, the engaging sections of the base and strengthening member being rigidly secured together throughout the length of the arm and having bolt holes therethrough, and insulator supporting pins secured to the 20 back of the base by bolts passing through said holes.

In witness whereof, I hereunto subscribe my name this 27 day of April, A. D., 1914.

CHARLES L. PEIRCE, JR.
